UNITED STATES PATENT OFFICE.

JESSE A. NELSON, OF ELLSWORTH, IOWA.

DESIGN FOR AN ELECTRIC LAMP.

49,439.

Specification for Design.

Patented July 25, 1916.

Application filed April 11, 1916. Serial No. 90,510. Term of patent 7 years.

To all whom it may concern:

Be it known that I, JESSE A. NELSON, a citizen of the United States, and resident of Ellsworth, in the county of Hamilton and State of Iowa, have invented a new, original, and ornamental Design for an Electric Lamp, of which the following is a specification, reference being had to the accompanying drawing, forming part thereof.

The figure shows a perspective view of an electric lamp embodying my invention.

I claim:

The ornamental design for an electric lamp, as shown.

Des Moines, Iowa, March 13, 1916.

JESSE A. NELSON.
